UNITED STATES PATENT OFFICE.

IRA B. CARTWRIGHT, OF MINONG, WISCONSIN.

FOLDABLE UMBRELLA.

1,109,736.

Specification of Letters Patent.

Patented Sept. 8, 1914.

Application filed October 29, 1913. Serial No. 798,003.

To all whom it may concern:

Be it known that I, IRA B. CARTWRIGHT, a citizen of the United States, residing at Minong, in the county of Washburn and 5 State of Wisconsin, have invented a new and useful Foldable Umbrella; and I do hereby declare the following to be a full, clear, and exact description of the invention, such as will enable others skilled in 10 the art to which it appertains to make and use the same.

This invention relates to a new and useful foldable umbrella.

An object of the invention is the provision of an improved foldable umbrella comprising desirable and practical features of construction.

In practical fields the details of construction may necessitate alterations, to which 20 the patentee is entitled, provided the alterations fall within the scope of what is claimed.

The invention comprises further features and combination of parts, as hereinafter set 25 forth, shown in the drawings and claimed.

In the drawings:—Figure 1 is a view showing the improved foldable umbrella open. Fig. 2 is a view showing the same collapsed. Fig. 3 is an enlarged detail view 30 of the sectional umbrella stick. Fig. 4 is a detail view showing the connection between the ribs and the stays.

Referring more particularly to the drawings, 1 designates the umbrella stick, which 35 comprises three telescopic sections, a ferrule section 2, a handle section 3, and an intermediate joining section 4. When the handle section is extended, it is secured in place by the threaded connections 5. The 40 joining section 4 is provided with a longitudinal vertical slot 6, which receives the lug 7 of the ferrule section 2, thereby preventing the ferrule section from twisting. One end of the slot 6 terminates in a transverse slot 45 8, to receive the spring catch 9 of the sleeve runner 10. By means of the catch 9 the sleeve runner is held in place when the umbrella is open. This spring catch not only holds the runner in place, but also holds 50 the ferrule section extended. In adjusting the parts of the stick, when opening the umbrella, the spring catch 9 is manipulated so as to remove it from the path of the lug 7,

that is, when extending the ferrule section 2. After the ferrule section 2 has been extended, the spring catch 9 is allowed to assume its normal position, in the path and under the lug 7. In this manner the ferrule section 2 is held extended.

The ferrule section 2 is provided with a cap plate 11, to which the ribs 12 are connected, as shown at 13 in the usual manner. Each rib 12 comprises two parts 14 and 15, the part 14 has a bifurcated end 16, in the arms or forks of said bifurcated end, the part 15 is pivoted by means of the pin 17. The arms or forks are designated by the numeral 18. The section 15 is constructed with an extension 19 disposed at an obtuse angle to the other portion of the section 15. 70 To each extension 19 one end of each stay 21 is pivoted as at 22, while the other end of each stay is pivoted in the usual manner to the sleeve runner 10, as shown at 23. The end of each stay which is pivoted to each extension 19 is bifurcated, and the forks 24 of said bifurcation abut against the forks 18 of the bifurcated end 16 of the section 14 of the rib, that is, when the umbrella is open, in order to reinforce the structure. 80

Upon referring to Fig. 1 when the umbrella is open, it will be seen what positions the relative parts assume, and upon referring to Fig. 2, which shows the umbrella folded, it will be seen what are the relative positions of said parts. When the umbrella is collapsed as shown in Fig. 2, the ribs are clamped together by the strap 26, while the extensions 19 are held in place by the flange 27 of the handle section 1 of the stick, which handle section 1 also threads in place as at 28 when the sections of the stick are collapsed.

The invention having been set forth, what is claimed as new and useful is:—

In a foldable umbrella, a stick comprising a handle section, a ferrule section and an intermediate joining section having a vertical slot, one end of which terminates in a transverse slot, said sections being telescopic, the ferrule section having a lug moving in said vertical slot, a sleeve runner on the intermediate joining section and provided with a spring catch to engage the transverse slot to hold the sleeve runner at one end of the intermediate section, said

spring catch engaging under the lug of the ferrule section to hold the same extended in position, collapsible ribs connected to the upper end of said ferrule section and connections between the ribs and the sleeve runner.

In testimony whereof I have signed my

name to this specification in the presence of two subscribing witnesses:

IRA B. CARTWRIGHT.
